UNITED STATES PATENT OFFICE.

CHARLES Y. KNIGHT, OF PASADENA, CALIFORNIA, ASSIGNOR TO THE KNIGHT-AMERICAN PATENTS COMPANY, OF CHICAGO, ILLINOIS, A CORPORATION OF DELAWARE.

ENGINE PISTON.

1,418,719.

Specification of Letters Patent. Patented June 6, 1922.

Application filed June 12, 1918. Serial No. 239,500.

To all whom it may concern:

Be it known that I, CHARLES Y. KNIGHT, a citizen of the United States, residing at Pasadena, in the county of Los Angeles and State of California, have invented certain new and useful Improvements in Engine Pistons, of which the following is a specification.

This invention relates to pistons for engines of various types and especially for internal combustion engines, and has for its object the provision of a device of the class named which shall be of improved construction and operation.

The invention is exemplified in the combination and arrangement of parts shown in the accompanying drawing and described in the following specification, and it is more particularly pointed out in the appended claims.

In the drawing—

Fig. 1 is a longitudinal sectional view of an engine piston of the ordinary trunk type showing my invention applied thereto; and

Fig. 2 is a section of the piston shown in Fig. 1.

In engine construction it is well known that pistons should be designed for lightness, speed, tightness of fit, and silence of operation, and the difficulties in securing all of these characteristics are well known to engine builders. In order to secure lightness the effort has been to construct pistons of metal which has this property, such as aluminum, or some aluminum compound or alloy, but it is usual to make the cylinder itself of cast iron since the cylinder does not reciprocate and does not require the same degree of lightness as the moving parts. Where an aluminum piston is used in a cast iron cylinder it has heretofore been necessary to sacrifice some of the other characteristics named above because of the fact that iron and aluminum vary greatly in their coefficient of expansion, the expansion of aluminum being much greater under the influence of the heat produced in the cylinder than is that of the cylinder itself. For this reason it has been necessary to allow a very considerable clearance between the aluminum piston and the cylinder walls in order that the piston will not stick when it reaches the temperature it attains under running conditions. This means that the piston must necessarily be loose in the cylinder

when the engine is starting, and this looseness in turn gives rise to objectionable noises at such times.

My invention contemplates an arrangement of parts that shall permit of the construction of the piston from a light metal, such as aluminum, and yet shall so regulate the expansion of this piston that it shall conform to the expansion of its cooperating cylinder made of a different metal. The manner in which this result is secured will best be understood from a description of the embodiment of the invention illustrated in the drawing, in which the numeral 1 designates a piston of the ordinary trunk type having the usual piston ring grooves 2 and gudgeon pin 3. The piston may be made of aluminum or a similar light metal and operates in the cylinder 4 of cast iron, or of whatever metal the manufacturer wishes to use for this purpose. Just below the gudgeon pin 5 the interior of the piston 1 is provided with a circumferential groove 6 which has a rib 7 adjacent the inner side thereof, and a smaller rib 8 adjacent its outer edge. The rib 8, projects very slightly above the inner wall of the piston and is formed to provide a beveled portion on its outer side. A ring 9 is made of cast iron if the cylinder walls are cast iron, or if the cylinder is of some other material, the ring 9 is made of the same material so that its coefficient of expansion shall be the same as that of the cylinder. The ring 9 at ordinary temperatures has an outer diameter slightly greater than the normal inner diameter of the groove 6 in the piston. The ring is forced into position in the groove under heavy pressure so that the walls of the piston are placed under tension and stretched outwardly giving the piston a diameter, adjacent the ring, somewhat greater than that which it would normally have were the ring omitted. In order to facilitate the expansion of the piston under the internal pressure produced by the ring 9, a series of slits 10 may be cut through the piston wall in various spaced positions around its periphery, as shown in the drawing. In place of slits other means for weakening the cylinder walls to permit expansion will readily occur to those skilled in the art, or the ring may be forced into place without any such provision, reliance being had upon the elasticity of the metal itself to permit the necessary expansion under the pressure of the ring.

When a piston, constructed as described, is subjected to the heat produced in the engine, the ring 9 will expand at the same rate as the cylinder in which the piston operates, and the expansion of the piston, adjacent the ring, will be controlled by the ring, since the tension in the walls of the piston will hold these walls tight against the exterior of the ring, and the more rapid expansion of the metal in the piston will merely tend to relieve this tension as the temperature increases instead of moving the walls outwardly toward the cylinder. In this way the piston may be made to fit quite closely to the walls of the cylinder at ordinary temperatures, and since its rate of expansion will be controlled by the ring 9, which expands at the same rate as the cylinder, the fit will continue to be the same for all temperatures to which the engine is subjected.

I claim:—

1. In combination, a piston, a cylinder in which said piston operates, said piston and cylinder being composed of metals having different co-efficients of expansion, and a member within said piston and arranged to exert outward pressure thereon to control the expansion of said piston under changing degrees of temperature.
2. In combination, a cylinder, a piston arranged to operate within said cylinder, said piston and cylinder being composed of different metals, and a member composed of a metal having a co-efficient of expansion similar to that of said cylinder and fitted within said piston and exerting outward pressure thereon to control the expansion and contraction of said piston under changing temperatures within said cylinder.
3. In combination, an iron cylinder, an aluminum piston arranged to operate within said cylinder, said piston having an internal circumferential seat therein, an iron ring fitted under pressure within said seat and having an external diameter sufficient to exert outwardly directed force on the interior of said piston to hold said piston in expand-

ed position under ordinary temperatures and to control the expansion of said piston when heated, the walls of said piston being weakened to permit expansion thereof under the pressure exerted by said ring.

4. An expansible piston comprising a head portion, and a cylindrical portion having a circular groove formed in the inner surface thereof; and an annular member having a normal unexpanded diameter greater than the diameter of the circular groove adapted to be forced into the groove formed in the cylindrical portion of the piston and retained in position thereby for expanding only the intermediate cylindrical portion of the piston.

5. An expansible piston comprising a head portion, and a cylindrical portion having a circular groove formed in the inner surface thereof; and a closed ring adapted to be forced into the groove formed in the cylindrical portion of the piston and retained in position thereby for expanding the cylindrical portion of the piston.

6. An expansible piston comprising a head portion and a cylindrical portion, provided with vertical slits, terminating short of the lower end of the cylindrical portion, a groove formed on the inner surface of the cylindrical portion intermediate the ends of the slits, and an endless expanding ring adapted to be forced into the groove and to expand evenly the slotted portion of the piston.

7. An expansible piston comprising a head portion and a cylindrical portion, said cylindrical portion comprising an upper and lower sections of unbroken metal, and a slotted portion intermediate said sections, a circular groove formed in the inner surface of the slotted portion and an annular member forced into the groove and adapted to expand the slotted portion of the cylindrical portion.

In testimony whereof I have signed my name to this specification on this 28th day of February, A. D. 1918.

CHARLES Y. KNIGHT.
